UNITED STATES PATENT OFFICE.

WINSLOW W. GUPTILL, OF BOSTON, MASSACHUSETTS.

CHECK-PUNCHING MACHINE.

SPECIFICATION forming part of Letters Patent No. 411,744, dated September 24, 1889.

Application filed December 3, 1888. Serial No. 292,539. (No model.)

To all whom it may concern:

Be it known that I, WINSLOW W. GUPTILL, a citizen of the United States, residing at Boston, in the county of Suffolk and State of Massachusetts, have invented certain new and useful Improvements in Check-Punching Machines, of which the following is a full, clear, and exact description, reference being had to the accompanying drawings, making part of this specification, in which—

Figure 1 is a front elevation of my improved check-punching machine. Fig. 2 is a longitudinal vertical section of the same on the line xx of Fig. 1. Fig. 3 is a transverse vertical section of the same on the line yy of Fig. 2. Fig. 4 is a horizontal section of the same on the line zz of Fig. 1. Fig. 5 is a sectional detail on the line ww of Fig. 1.

My invention has for its object to improve the construction of that class of machines known as "check-punching" machines, which are employed for punching out figures in checks, drafts, &c., to designate the amounts for which they are drawn, and thereby prevent them from being raised or otherwise tampered with; and to this end my invention consists in certain novel combinations of mechanical devices and details of construction, as hereinafter more fully set forth, and pointed out in the claims, whereby a simpler, cheaper, and more desirable machine of this character is produced than is now in ordinary use.

In the said drawings, A represents the frame or casing of the machine, a portion of which extends out in front to form a feed-table b for supporting the check while being punched. Within suitable bearings in the casing A is supported a horizontal shaft B, to the front end of which is secured a wheel C, provided with a series of flat faces, as seen dotted in Fig. 1, each of these faces having secured to it by means of screws d a removable die-plate e. Immediately over the shaft B is placed a horizontal shaft D, the front end of which is supported in a box c, which slides vertically in suitable guides and is supported by a spiral spring f, placed beneath it, as seen in Fig. 2, the rear end of this shaft being supported in a bearing g in the casing, suitably formed to allow the shaft to be tilted up and down, for a purpose to be hereinafter described. To

the front end of the shaft D is secured a punch-wheel G, to the periphery of which, at suitable distances apart, are secured groups 55 of punches a, arranged to form the figures and characters which it is desired to punch out of the check, the die-plates e on the wheel C having their dies or apertures h formed to correspond and act in conjunction with the 60 punches or dies a of the wheel G when the latter is depressed by mechanism to be presently described. To the rear ends of the shafts B D are secured gears i k, which engage with each other, and to the front end of 65 the shaft B, outside the casing, is secured a serrated hand-wheel H, by turning which the punch and die wheels G C, through the connections described, are rotated simultaneously to bring any desired punch a into position to cut out a corresponding figure on the check when the punch-wheel is depressed, the front face of the punch-wheel being provided with figures and characters, as seen in Fig. 1, to indicate the positions of the punches. 70 l is an index-finger or pointer, which, when any figure or character is brought immediately thereunder, indicates that the punch corresponding to said figure or character is in the proper position to punch the check. 75 This pointer l is secured to a ring m, which is screwed to the casing in front of the punch-wheel, and serves to conceal the punches a from view and form an ornamental finish at 80 this point.

n , Fig. 2, is a friction spring-stop, which engages with a series of rounded or inclined notches p on the rear face of the punch-wheel, and as said wheel is rotated serves to center each punch exactly over its die in the wheel 90 C, thereby insuring the proper co-operation of the punches and dies.

q is a stripper-plate or clearer, which is placed between the rotary punch and die wheels, and is provided with an aperture 95 for the passage of the punches, said stripper acting in the usual manner to clear the punches from the check as they ascend.

I will now describe the manner in which the punch-wheel G is depressed to cause it to cut out the figures or characters on the check.

r is a horizontal shaft extending transversely across the machine and provided at

- its right-hand end outside the casing with a hand-lever *s*, Fig. 1, provided with a knob or handle *t*, placed in a convenient position to be grasped by the hand. To this shaft *r* is secured an arm or toe *u*, which rests upon the sliding box or bearing *c* of the shaft *D*, and thus as the hand-lever *s* is pushed down the arm *u* depresses the box *c*, carrying with it the punch-wheel *G*, the lower punch of which, 5 in connection with its die, then cuts out the corresponding figure on the check, as required, after which the hand-lever *s* is released, when the spring *f* will raise the punch-wheel *G*, and the die and punch wheels are then rotated, 10 as before described, to bring the punch and die corresponding to the figure or character which it is next desired to cut out into its proper operative position.
- I will now describe the manner in which the 15 check is automatically fed forward after each figure has been punched out in order to bring it into the proper position for the next figure or character to be cut out. To the shaft *r* is secured a long arm or lever *a'*, the outer end 20 of which is pivoted to the upper end of an arm or bar *I*, of the form seen in Fig. 3. This bar *I* is pressed in the direction of the arrow, Fig. 3, by a light spring *c'*, the outer end of which is provided with flanges *S*, Figs. 25 2 and 3, which fit over the edges of the bar and serve as guides therefor, and also to keep the bar always in contact with the spring. The lower end of the bar *I* is bifurcated, 30 two fingers 12 14, of different lengths, being thus formed, whereby the lower end of the bar is adapted to engage with a series 35 of pins *d'*, projecting horizontally from the side of a wheel *K*, secured to the end of the horizontal shaft *e'* of a feed-roll *f'*, Fig. 2, 40 immediately over which is placed a pressure-roll *g'*, mounted on a shaft 15. The shaft *e'* of the feed-roll *f'* is supported in such manner as to allow it to be pressed down against the resistance of a spring, as seen 45 dotted in Fig. 1, by taking hold of a knob or handle 20 at the outer end of said shaft, which movement of the feed-roll allows the check to be introduced between said roll and the roll *g'* above. The parts being in the position shown in Figs. 2 and 3, when the punch-operating lever *s* is depressed the bar *I* is raised by the arm *a'* until its lower bifurcated end is carried up to a sufficient height to engage the next succeeding pin *d'* of the wheel 50 *K*, the spring *c'* yielding to permit this movement, and as soon as the shorter finger 12 at the end of the bar *I* clears this next pin *d'* above the spring *c'* forces the bar *I* inward in the direction of the arrow until the longer 55 finger 14 is brought into contact with said pin. As the punch rises after cutting out the figure or character the bar *I* commences to descend, and as soon as the punch on its ascent has cleared the paper the bifurcated end of 60 the bar *I* between the two fingers engages with this pin *d'* and moves the wheel *K* and feed-roll *f'*, thus feeding forward the check

a distance equal to that required between two figures or characters to be cut. As soon as the bar *I* has completed its downward movement the pin *d'* next above the one engaged is brought into contact with the inner side of the bar *I*, as seen in Fig. 3, which thus forms a stop for preventing the feed-roll from being rotated beyond the proper point by its own momentum. 70

On the right-hand side of the punch and die wheels is placed a printing device for printing the name and address of the drawer of the check or other desired matter. This 80 device consists of a printing-roll *L*, Figs. 3 and 5, mounted on a tilting shaft *h'*, supported at its front end by a spring *i'*, Fig. 5, and having a handle *k'*, by which it can be depressed to allow the check to be inserted 85 between the printing-roll *L* and the impression-roll *l'* above, and immediately beneath the printing-roll is placed an inking-pad *m'*, which is secured to a plate *n'*, supported on a short post *p'*, fitting within a tubular post 25 90 and surrounded by a spiral spring *q'*, which serves to keep the inking-pad up in a proper position to ink the types as the roll *L* is rotated, and by means of this device as the check is drawn forward by the feeding device just described it will receive the name or address or 95 other matter which it may be desired to print thereon. In order to prevent the check from being pushed in too far, suitable adjustable gages *r'* are provided on each side of the machine, which serve to regulate the position of the check and determine the distance from its edge of the figures or characters punched out and the printed matter produced by the 100 printing device. 105

What I claim as my invention, and desire to secure by Letters Patent, is—

1. In a check-punching machine, the combination of a rotary wheel provided with a series of dies and a rotary wheel carrying a 110 series of punches corresponding to said dies and having a movement toward and from said die-wheel, said die and punch wheels being mounted on shafts connected by gears, substantially as and for the purpose set forth. 115

2. In a check-punching machine, a rotary wheel carrying a series of punches and mounted on a shaft supported at its front end in a vertically-sliding box or bearing, said wheel having figures on its front side to indicate the positions of the punches, in combination with a rotary wheel having a series of dies corresponding to the punches and mounted on a shaft geared to the shaft of the punch-wheel, whereby the two wheels are adapted 120 to be rotated simultaneously by hand, a feed-table for supporting the check to be punched, a lever for depressing the punch-wheel to cause the punches carried thereby to pass through the paper, and a feeding device for 125 moving the check after each figure has been punched out, substantially as set forth. 130

3. In a check-punching machine, a rotary wheel mounted on a horizontal shaft and hav-

ing a series of straight faces, each provided with a removable die-plate, in combination with a rotary wheel carrying a series of punches and having a movement toward and from said die-wheel, said punch-wheel being mounted on a shaft geared at its rear end to the shaft of the die-wheel, a feed table or support, a stripper-plate or clearer placed between the punch and die wheels, and a feeding device for moving the check after each operation of the punch, all constructed and arranged to operate substantially as described.

4. In a check-punching machine, the combination of a rotary wheel carrying a series of removable dies and provided with a knob or hand-wheel for turning the same, a rotary wheel carrying a series of punches and having a movement toward and from the die-wheel, said die and punch wheels being mounted on shafts connected at their rear ends by gears, a hand-lever for depressing the punch-wheel, a spring for raising the same after each depression, a feed-table for supporting the check, a stripper-plate or clearer placed between the die and punch wheels, a printing device consisting of a printing-roll, a pressure-roll acting in conjunction therewith, and an inking device, the shaft of said printing-roll yielding downwardly and being adapted to be depressed by the hand to admit the check between the two rolls, and a feeding device for moving the check after each figure has been punched out, substantially as set forth.

5. In a check-punching machine, the combination of a rotary wheel carrying a series of removable dies and provided with a knob or hand-wheel for turning the same, a rotary wheel carrying a series of punches and having a movement toward and from the die-wheel, said die and punch wheels being mounted on shafts connected at their rear ends by gears, a shaft *r*, provided with a hand-lever *s* and having an arm *u*, bearing on the vertically-sliding box *c* of the shaft *D* of the punch-wheel *G*, and adapted to depress said wheel, and an arm or lever *a'*, connected with and operating the feeding device for moving the check after each figure has been punched out, substantially as set forth.

6. In a check-punching machine, the combination, with the rotary punch and die wheels operating substantially as described, of the printing device consisting of the printing and impression rolls *L* *l'*, the former mounted on a spring-supported downwardly yielding shaft *h'*, adapted to be depressed by hand to allow of the introduction of the check between said rolls, and an inking device for the printing-roll, substantially as set forth.

Witness my hand this 30th day of November, A. D. 1888.

WINSLOW W. GUPTILL.
